MERCHANDISE DISPLAY DEVICE

Lora McGraw, San Fernando, Calif., assignor to Glen Raven of California, San Fernando, Calif., a corporation of California

Application March 30, 1959, Serial No. 802,837

4 Claims. (Cl. 211—51)

This invention relates to display holders for merchandise and particularly to a form thereof suitable for holding merchandise of the form contained in envelopes or similar flat packages.

An object of the invention is to provide a merchandise displaying and holding means particularly adapted for holding varying quantities of articles of merchandise contained in individual, envelope-like containers and characterized by simplicity of construction, ability to continue to maintain the merchandise presented in an attractive manner as the quantity of the merchandise varies due to customer selection and repletion of merchandise.

Another object of the invention is to provide a merchandise displaying and holding means in which the foregoing objectives are realized in practice, and which is of neat and unobtrusive appearance with resultant concentration of customer attention on the merchandise displayed thereby.

A further object of the invention is to provide a merchandise displaying and holding means of simple construction and neat, unobtrusive appearance which is particularly adapted for holding and displaying a quantity of articles of merchandise contained in envelope-like containers and which readily permits customer selection and removal of articles of merchandise from the quantity contained therein, without disturbing the remaining articles.

With the foregoing objects in view, together with such additional objects and advantages as may subsequently appear, the invention resides in the parts, and in the construction, combination and arrangement of parts described, by way of example, in the following specification of a presently preferred embodiment of the invention, reference being had to the accompanying drawings which form a part of said specification and in which drawings:

Fig. 1 is a perspective view partly in section of a representative unit embodying the present invention, the merchandise being omitted therefrom,

Fig. 2 is a similar perspective view but showing a quantity of merchandise contained in the device,

Fig. 3 is an enlarged scale end elevational view of the device with the merchandise contained therein, as viewed, for example, from the right hand end of Fig. 2, and

Fig. 4 is an exploded view of the device shown in the preceding paragraphs with the component parts displayed in the approximate relation they occupy in the assembled device.

The illustrated embodiment of the invention comprises a base or back member 1 presenting a vertical front face; said back member being formed of rigid material which may be hardboard, plywood or even plastic, the size preferably being at least the size of the articles of merchandise in plan although as will be discussed hereinafter and as will be then apparent this back member may be of much larger size containing pluralities sets of the other

2

parts so that a single back member may hold a plurality of the merchandise holding devices.

The merchandise holding means in addition to the back member 1 comprises a bottom member 2 preferably formed from rigid transparent sheet plastic and comprising a generally horizontal portion 3, a rearward vertically extending flange portion 4 adapted to be secured to the back member 1 by any suitable means as, for example, screws 5, 5 passing therethrough and threadedly engaging the front face of the back member 1. Forwardly spaced from this flange member 4, the bottom member 2 includes a vertically extending front member 6 which extends upwardly parallel to the back member 1, the upper edge thereof being somewhat below the upper edge of the envelopes of merchandise M supported thereon. The front portion 6 additionally has openings 7, 7 extending therethrough disposed in axial alignment with the screws 5, 5 through which access may be had for assembling the bottom member 2 to the back member 1. It will be noted in Fig. 3 that in the illustrated embodiment of the invention, the underside of the bottom portion 3 of the member 2 is flush with the bottom edge of the member 1 whereby the device may be placed on a counter or the like for easy access to the merchandise by customers.

The merchandise M is held against movement horizontally edgewise by a retainer member 8 formed of a small metal rod, said rod being flattened at its mid-length portion as at 9 and provided with a hole through the flattened portion for reception of a screw 10 to secure it to the front face of the back member 1 at an elevation which is slightly below the upper edge of the envelopes of merchandise. The opposite ends of the rod 8 are bent on themselves in return bend loops 11, 11 and the ends of the rod are also flattened as at 12, 12 said flattened portions being provided with holes for reception of screws 13, 13 which secure the ends of the rod 8 to the back member 1 below the mid portion of the rod and slightly inwardly of the side edges of the envelopes of merchandise. The loop portions 11, 11 of the rod are bent at right angles as at 14, 14 so that the said loop portions extend parallel forwardly from the back member 1 at each side of the envelope packages of merchandise to retain them against lateral movement on the bottom member 2.

The merchandise envelopes M are maintained in yielding engagement with the front portion 6 of the bottom member 1 by a resilient spring 15 formed of a length of spring wire having looped ends 16, 16 which are disposed between the ends 12, 12 of the rod 8 and the front face of the back member 1 and through which the screws 13, 13 extend to secure both the rod 8 and the spring element 15 to the back member 1. The shape of the spring member 15 can best be described by saying that the length of wire is initially bent into V-shape with the apex 17 thereof at the mid-length of the wire. The ends of the spring thence extend upwardly, divergently over the portion of the rod 8 extending between the flattened portion 9 thereof and the adjacent bends 14, 14 therein and the spring 15 thence extends downwardly in rear of the front portion 6 of the bottom member 2, wherefore the apex portion 17 is constantly exerting an outward movement toward the inner face of the front portion 6 and therefor acting constantly to hold the envelopes of merchandise against the rear face of the front portion 6 of the bottom member 2 as best shown in Fig. 3. It will be apparent that by this configuration this spring member 15 can yieldingly hold a varying number of envelopes of merchandise varying from a quantity which will cause the apex portion 17 to be in substantial contact with the back member 1 to a single envelope and that these envelopes, whether one or many, will be main-

tained in an erect position against the front portion 6 while permitting ready removal of any one of them by a purchaser. At the same time, the ends 11, 11 of the rod member 8 serve to hold the envelopes of merchandise against lateral displacement.

It is particularly to be noted as best shown in Fig. 2 that the display device maintains the merchandise displayed with emphasis being placed upon the merchandise itself, the portions of the device exposed to view being relatively unobtrusive. It will further be apparent that while the back member 1 as here shown accommodates only a single set of the merchandise holding parts, a larger back member may be employed to carry a plurality of sets of such parts in any spaced relation desired.

While in the foregoing specification there has been disclosed a presently preferred embodiment of the invention, it is appreciated that in the light of such disclosure, changes and modifications will suggest themselves to those skilled in the art. Accordingly, it is not to be inferred that the invention is limited to the embodiment thus disclosed by way of the sample and it will be understood that the invention includes as well all such changes and modifications in the parts and in the construction, combination and arrangement of parts as shall come within the purview of the appended claims.

I claim:

1. A display holder for articles of merchandise contained in envelope-like containers comprising a rigid back member presenting a vertical front face, a bottom, merchandise supporting member formed of rigid sheet material comprising a vertically extending rear flange portion secured to said front face of said back member, a forwardly extending merchandise supporting portion and an upwardly extending front portion spaced forwardly from and disposed parallel to said front face of said back member, means for preventing edgewise lateral movement of merchandise envelopes on said horizontal portion of said bottom member comprising a rod having a horizontal portion secured to said back member above said horizontal portion of said bottom member and including portions thence extending horizontally forwardly at each side of said bottom member, and spring means secured to said back member constructed and arranged to yieldingly maintain the articles of merchandise in engagement with each other and pressed against the rear surface of said front portion of said bottom member.

2. A display holder for merchandise as claimed in

claim 1 in which securing means for said rod member serve additionally to secure said spring means to said front face of said back member.

3. A display holder for articles of merchandise contained in envelope-like containers comprising a rigid back member presenting a vertical front face, a bottom, merchandise supporting member formed of rigid sheet material and comprising an upwardly extending rear flange portion secured to said front face of said back member, a forwardly, horizontally extending merchandise supporting portion and an upwardly extending front portion spaced forwardly from and disposed parallel to said front face of said back member, means for preventing edgewise lateral movement of merchandise envelopes supported on said horizontal portion of said bottom member comprising a rod having a horizontal mid-length portion secured at the mid-length thereof to said back member above the plane of said horizontal portion of said bottom member and including end portions extending forwardly and thence downwardly and rearwardly in return bends disposed at each side of said bottom member above the horizontal portion of said bottom member and terminating in horizontal, laterally extending ends secured by screws to said front face of said back member, and spring means secured to said back member comprising a single length of wire doubled on itself and having its ends secured to said back member and having the doubled end thereof disposed to urge articles of merchandise supported on said horizontal portion of said bottom member into engagement with each other and against the rear face of said front portion of said bottom member.
4. A merchandise display holder as claimed in claim 3 in which said spring means comprises a length of spring wire bent on itself at its mid-length in a V configuration and having screw receiving loops at each end thereof, said loops being entered by the screws which secure said ends of said rod to said front face of said back member and said wire thence extending upwardly over the horizontal mid-length portions of said rod and thence downwardly in rear of said front portion of said bottom member.
